Primary Examiner — Mark A Goodwin

(57) **CLAIM**

The ornamental design for a gold processing wash system, as shown and described.

DESCRIPTION

FIG. 1 is a top front perspective view of gold processing wash system showing my new design;
FIG. 2 is a top front perspective view thereof;
FIG. 3 is a bottom front perspective view thereof;
FIG. 4 is a bottom front perspective view thereof;
FIG. 5 is a top rear perspective view thereof;
FIG. 6 is a top rear perspective thereof;
FIG. 7 is a bottom rear perspective view thereof;
FIG. 8 is a bottom rear perspective view thereof;
FIG. 9 is a front elevational view thereof;
FIG. 10 is a rear elevational view thereof;
FIG. 11 is a right elevational view thereof;
FIG. 12 is a left elevational view thereof;
FIG. 13 is a top plan view thereof;
FIG. 14 is a bottom plan view thereof; and,
FIG. 15 is a detailed view taken along line **15-15** in FIG. 6.
